CARTON FOR BOTTLE OR SIMILAR ARTICLE

Richard G. Gelak, Cherry Hill, and Vero Ricci, Collingswood, N.J., assignors to E. I. du Pont de Nemours and Company, Wilmington, Del.

Filed Aug. 22, 1969, Ser. No. 18,805

Term of patent 14 years

Int. Cl. D9—04

U.S. Cl. D9—225

FIG. 1 is a top view of a carton for bottle or similar article showing our new design.

FIG. 2 is a front view thereof.

FIG. 3 is a side view thereof.

The sides of the carton opposite the front and side views shown in FIGS. 2 and 3 are substantially the same as the side view shown in FIG. 3.

FIG. 4 is a bottom view thereof.

FIG. 5 is a cross-sectional view thereof taken at section 5—5 of FIG. 3.

We claim:

The ornamental design for a carton for bottle or similar article, substantially as shown and described.
